IRON CORD HOLDER

Olin Nelson, Superior, Wis.

Application March 19, 1949, Serial No. 1,501

Term of patent 3½ years

(Cl. D49—6)

To all whom it may concern:

Be it known that I, Olin Nelson, a citizen of the United States of America, residing at Superior, in the county of Douglas and State of Wisconsin, have invented a new, original, and ornamental Design for an Iron Cord Holder, of which the following is a specification, reference being had to the accompanying drawing, forming part thereof.

In the drawing

Fig. 1 is a front elevational view of an iron cord holder, showing my new design;

Fig. 2 is a side elevational view of Fig. 1.

Fig. 3 is a sectional view on the line 3—3, Fig. 2.

Fig. 4 is a sectional view on the line 4—4, Fig. 2.

Fig. 5 is a top plan view of the upper pivotal arm of the iron cord holder, and

Fig. 6 is a rear end elevational view of Fig. 5.

I claim:

The ornamental design for an iron cord holder, as shown.

OLIN NELSON.
